UNITED STATES PATENT OFFICE.

JOHN W. MEAKER, OF DETROIT, MICHIGAN.

EXPLOSIVE-ENGINE.

1,023,088.

Specification of Letters Patent.

Patented Apr. 9, 1912.

Application filed June 9, 1910. Serial No. 565,908.

To all whom it may concern:

Be it known that I, JOHN W. MEAKER, a citizen of the United States of America, residing at Detroit, in the county of Wayne 5 and State of Michigan, have invented certain new and useful Improvements in Explosive-Engines, of which the following is a specification, reference being had therein to the accompanying drawings.

10 This invention relates to explosive engines of the four-cycle type and more particularly to an arrangement of the cylinder whereby the interior of the cylinder and piston and adjacent parts are thoroughly cooled and 15 whereby an impulse is given to the piston rod on each down stroke.

The invention consists in the matters hereinafter set forth, and more particularly pointed out in the appended claims.

20 Referring to the drawings, Figure 1 is a view in transverse section through the cylinder and adjacent portions of a motor that embodies features of the invention showing the position of the parts at the end of the 25 up-stroke; Fig. 2 is a view of a motor showing a pair of coupled cylinders one in section and one in elevation; Fig. 3 is a view of a modification of the motor.

In the drawings, a cylinder 1 that is open 30 at both ends rests at its lower extremity on a base 2 with crank case 3 in which a main shaft 4 is journaled. A sleeve 5 has a flange 6 on its lower open end which is reciprocated in a counterbored or enlarged portion 35 7 of the lower part of the cylinder, the body of the sleeve fitting the body of the cylinder and a tubular extension 8 sliding in a corresponding reduced upper end 9 of the cylinder. Packing rings 10 on the flange 6 and similar members 11 on the extension 8 prevent leakage. A valve chamber 12 is formed on the upper portion of the cylinder with its interior in communication with the annular space formed above the upper face 45 of the body of the sleeve and around the extension 8. The lower valve chamber 13 is likewise formed on the cylinder so that its interior communicates with the annular space between the upper face of the flange 50 10 and the counterbored face 14 of the cylinder and around the sleeve 5. An intake port 15 in the upper chamber and a similar port 16 in the lower chamber are controlled by inlet valves 17 and 18 operated through 55 any preferred mechanism, as for example, spring pressed tappets 19 and 20 which are

respectively reciprocated through the medium of a cam shaft 21 driven in timed relation to the main shaft through suitable mechanism not shown herein. Exhaust 60 ports 22 and 23 in the respective chambers are similarly controlled by exhaust valves driven by suitable means, as for example, spring pressed tappets 24 and 25 reciprocated by the shaft 21. Each sleeve 5 is connected by a wrist pin 26 and a piston rod 27 to crank arms 28 of the main shaft in the usual manner.

Any suitable ignition system is used for exploding the charges in the two annular spaces which form the compression chambers. Such means are not indicated and may be of any preferred form.

In operation the explosion in each annular space forming a compression chamber is followed by the scavenging, intake and compression in the usual four-cycle rotation, but the cycles alternate so that the sleeve is given an impulse at each of its downward strokes. This, in the two-cylinder arrangement such as indicated in Fig. 2, gives the same torque to the shaft as in the four-cylinder four-cycle engine of conventional type. In addition to this advantage of space and weight and diminution of running parts, the open ended sleeve to which the main shaft is coupled is thoroughly cooled by the movement of air through its bore occasioned by the open ends. This likewise cools the cylinder which may be outwardly water jacketed as herein indicated or may have the usual radiating surface for air cooling.

While the construction just described is preferable it obviously may be modified to give a single downward impulse to the piston on every other stroke as in the conventional four-cycle motor, and such arrangement of parts is shown in Fig. 3 wherein an open ended cylinder is secured on a crank case and base 30 and has its lower portion counterbored. An open ended sleeve 31 is reciprocable in the upper portion of the cylinder 30 and has a flange 32 at its lower end engaging the counterbored portion. Packing rings 33 on the upper portion of the sleeve and similar members 34 on the flange insure a tight joint and provide an annular compression chamber indicated at 35 into which ducts controlled by valve mechanism indicated at 36 open from the source of fuel supply. This particular form of construc-

tion has a further advantage in that the crank shaft 37 of the engine may be coupled by a piston rod 38 to a wrist pin 39 which engages the sleeve above the upper set of 5 rings 33. As a result of this construction compression and ignition take place when the wrist pin bearings are remote from the compression chamber and this eliminates liability to leakage which is one of the difficulties current in explosive engines of 10 conventional type.

It may be desirable to regulate the amount of air circulation through the sleeve in order to allow the cylinder to be warmed to the 15 most efficient degree. One method of accomplishing this is by placing a damper 40 in the upper end of the tubular sleeve (as indicated in Fig. 2) so arranged as to reduce to a greater or less extent the size of the 20 sleeve opening. Any preferred form of shutter or damper may be employed for this purpose.

Obviously changes in the details of construction may be made without departing 25 from the spirit of the invention and I do not care to limit myself to any particular form or arrangement of parts.

What I claim as my invention is:—

1. In an explosive engine, an open ended 30 cylinder having an enlarged lower portion and a contracted upper portion, an open ended sleeve reciprocable therein having portions that fit the corresponding portion of the cylinder, means for partially closing

the bore of the sleeve, and a crank shaft 35 operatively coupled to the sleeve.

2. In an explosive engine, an open ended cylinder having an enlarged lower portion and a contracted upper portion, an open ended sleeve reciprocable therein having 40 portions that fit the corresponding portions of the cylinder, means for partially closing the bore of the sleeve, a valve chamber in communication with the annular space formed between the sleeve and cylinder, a 45 crank shaft operatively connected to the sleeve, and intake and exhaust valves in the chamber operatively connected to the shaft to open in timed relation to the movement of the sleeve.

3. In an explosive engine, a closed base, open ended cylinders secured thereon, each cylinder having an enlarged lower portion and a contracted upper portion, an open ended sleeve reciprocable in each cylinder 55 having portions that fit the corresponding portions of the cylinder, a crank shaft journaled in the base adjacent the cylinders and operatively coupled to each sleeve, and means for partially closing the bore of one 60 or more of the sleeves.

In testimony whereof I affix my signature in presence of two witnesses.

JOHN W. MEAKER.
